UNITED STATES PATENT OFFICE.

CHARLES EDWIN HAYNES, OF MINNEAPOLIS, MINNESOTA.

CAR-COUPING.

SPECIFICATION forming part of Letters Patent No. 448,427, dated March 17, 1891.

Application filed November 4, 1890. Serial No. 370,271. (No model.)

To all whom it may concern:

Be it known that I, CHARLES EDWIN HAYNES, a citizen of the United States, and a resident of Minneapolis, county of Hennepin, and State 5 of Minnesota, have invented certain new and useful Improvements in Car-Couplers, of which the following is a specification.

This invention relates to improvements in that class of car-couplers of which the "Hinson" is a type, and in which a pair of horizontal pivoted interlocking jaws are employed for effecting the coupling. In couplers of this class prior to this invention it has been customary to pivot the swinging coupling-jaw 10 upon a pin passing through the draw-head, and to cause the automatic opening of the coupler by providing double inclines upon the pivoted jaw and the draw-head, respectively, which devices have not proven entirely 15 satisfactory because of the friction and wear of such devices, which tend to prevent the free swinging open of the pivoted jaw, and especially is this true in wintry or dusty weather.

25 The object of this invention is to reduce the number of parts to the minimum, and hence promote the simplicity of the device, and at the same time reduce the friction between the moving parts to the minimum with- 30 out lessening, but on the contrary promoting, the strength and durability of the coupler as a whole. This object is attained by the devices illustrated in the accompanying drawings, in which—

35 Figure 1 represents a plan view of a pair of couplers in position for coupling; Fig. 2, a central horizontal section through the same, showing them coupled; Fig. 3, a transverse vertical section on the line 3 3 of Fig. 1; Fig. 40 4, a side elevation of one of the couplers, showing the jaw closed; Fig. 5, a similar view showing the jaw open; Fig. 6, a detail plan view of one of the jaws; Fig. 7, a detail plan view of the bearing or socket for the 45 jaw-trunnion; Fig. 8, a sectional elevation showing the relation of the jaw and its trunnion to the bearing; Fig. 9, a horizontal section on the line 9 9 of Fig. 8, more particularly showing the position of the trunnion in 50 its bearing when the jaw is closed; and Fig. 10, a similar view showing the same when the jaw is open.

Similar letters of reference indicate the same parts in the several figures of the drawings.

As the couplers on adjacent cars are exact 55 duplicates of each other, in describing them in detail I will refer to only one coupler.

Referring by letter to the accompanying drawings, A indicates the draw-head, which may be of any suitable construction, as well 60 as the jaw B, although for convenience of illustration I have shown in the drawings the Hinson couplers, in which the jaw, of L shape, is pivoted at the elbow within the draw-head upon trunnion C on the upper and 65 lower sides thereof, and when engaged by the opposing coupler, as illustrated in Fig. 2, is caught and locked at its inner end by a spring-actuated pin D. The trunnions, instead of 70 being round, are oblong in cross-section, and work in suitable bearing-sockets E in the draw-head, to which they gain access through obliquely-arranged slots or channels F at one 75 side of the head of substantially the same diameter as the width of the trunnion, but less than the length thereof, so that the trunnion cannot become disengaged from the bearing without being forcibly turned to register lengthwise with the slot.

So much of this coupler as has been de- 80 scribed is substantially identical with the Hinson coupler, except a difference in the direction of length of the trunnions in cross-section and the location of the channels or slots leading into the trunnion-bearing, and 85 with such a construction the jaws would remain in any position to which they are moved, either mechanically or manually, whether partly or entirely opened or closed; but it is the purpose of this invention to have the jaws 90 automatically open immediately they are disengaged from each other or from their locking devices, so as to normally assume the open position necessary for coupling. To this end at the opposite sides of the lower trunnion-bearing is located a pair of oppositely-inclined bearing-pieces G, upon which the lower trunnion rests, the edges thereof being rounded, so as to ride the inclines with less friction and wear. In opening and closing 95 the jaw the trunnion rides down and up these incline bearings, without, however, leaving the socket, and of course slightly elevating and lowering the jaw in the operation, the bearings 100

being so arranged radially within the socket that when the jaw is closed, as illustrated in Figs. 4, 8, and 9, the trunnion still rests upon the bearings, but near the top of the incline, so that immediately the jaw is released the gravity thereof will cause the trunnion to ride down the inclines, and by such action to turn and open the jaws, as illustrated in Fig. 10; but in the coupling operation the trunnion will 5 be again caused to ride up the incline bearings by the turning of the jaw into position for locking—that is, inclosing it—thus leaving the trunnions in such position upon its 10 bearings that the jaw will be compelled to automatically assume an open position ready 15 for coupling as soon as released by the opposing jaw or the locking device. Obviously the end of the trunnion, as well as the bearing thereof in the socket may have many other 20 contours than that described and illustrated; but all such are within the scope of my invention so long as they cause the automatic opening 25 of the jaw.

A coupler embodying my invention is simple, economical, and effectual, may be applied to any coupler employing a horizontal pivoted jaw, and, in fact, may be added to couplers now in use at very small expense, besides which it possesses the important advantage 30 of causing the coupler, when not in use, to automatically assume and maintain a position in readiness for coupling without having to be manipulated either by hand or mechanically, as has heretofore been necessary.

It will of course be understood that this invention is likewise applicable to couplers in which the jaw is pivoted or swings upon the pin instead of upon trunnions, the end of the 35 pin working in a bearing-socket in the draw-head in the same manner as the trunnion

now operates, the changes necessary to adopt a coupler so constructed for operating upon this principle being obvious to any one skilled in the art to which my invention pertains. 45

Having described my invention, what I claim, and desire to secure by Letters Patent, is—

1. In a car-coupler, the combination, with the draw-head provided with bearing-sockets, 50 of a coupling-jaw, trunnions thereon working in said sockets, and inclined end bearings for the trunnion in the lower socket, substantially as described.

2. In a car-coupler, the combination, with 55 the draw-head provided with bearing-sockets, the lower one of which has oppositely-inclined bearings at the sides thereof, of a coupling-jaw, oblong trunnions thereon working in said sockets, the lower one of which rides said inclined bearings and is so arranged as to rest 60 near the top of the inclines when the jaw is closed, substantially as described.

3. In a car-coupler, the combination, with a draw-head provided with bearing-sockets, 65 the lower end of which has oppositely-inclined bearings therein, of a coupling-jaw, oblong trunnions thereon working in said sockets, the lower one of which rides said inclined bearings and is so arranged as to rest near 70 the top of the inclines when the jaw is closed, and obliquely-arranged slots or channels at one side of the draw-head leading into the bearing sockets thereof, said slots being of substantially the same diameter as the width 75 of said trunnions, but less than the length thereof, substantially as described.

CHARLES EDWIN HAYNES.
